CLAIM

The ornamental design for a decorator blind, as shown and described.

DESCRIPTION

FIG. 1 is an environmental view, somewhat in perspective, of a decorator blind showing my new design; FIG. 2 is a front view with the rear view being a mirror image thereof;

FIG. 3 is a top view thereof;

FIG. 4 is a bottom view thereof;

FIG. 5 is a left view thereof; and,

FIG. 6 is a right view thereof.

The broken line showing of the window and the windowsill in FIG. 1 is for illustrative purposes only and forms no part of the claimed design.

FIG. 1

FIG. 2

FIG. 3

FIG. 4

FIG. 5

FIG. 6
